UNITED STATES PATENT OFFICE.

CHARLES M. ABBOTT, OF WATERTOWN, MASSACHUSETTS, ASSIGNOR TO SAMUEL CABOT, INC., OF BOSTON, MASSACHUSETTS, A CORPORATION OF MASSACHUSETTS.

SHINGLE-ABRADING MACHINE.

Application filed October 16, 1925. Serial No. 62,929.

In this application I present an invention relating to mechanisms for performing certain operations, notably for surfacing shingles or like material. Interpreted as such we may take as a specific example a machine for the production of an imitation rift shingle. The rift shingle or shake has an historic setting in the lumber industry and has occupied a unique position as being in demand and yet commercially unavailable.

Without discussing the well known problem of the article, I deliberately select it as an example because it affords an extreme and specific test of my invention, although it is capable of infinite adaptation to other fields of work.

In the illustrative field selected, it is to be noted that the result to be secured is an abraded shingle having a scored surface mechanically produced in a certain definite relation to a previous standard system of sawing by which it transforms the original stereotyped product with a highly specialized product favorably comparable with the highly expensive commercially unavailable shingles known as "hand split shakes".

As an example of a machine capable of the commercial production of such shingles, I have shown in the accompanying drawings an embodiment well adapted to commercial production so as to be available in any lumber yard and thus economically adapted to supply such shingles promptly on order.

Without limitation or limiting detail, I have set forth in the accompanying drawings a machine well adapted to the commercial production of shingles and capable of performing the method of my invention. Throughout the specification and drawings like reference characters are employed to indicate corresponding parts, and in these drawings:

Fig. 1 is a side elevation of such a machine.

Fig. 2 is a plan view thereof.

Fig. 3 is an end elevation at the abrading end of the machine.

Figs. 4 and 5 are somewhat diagrammatic side elevations showing feeding and abrading steps, respectively.

Fig. 6 is an enlarged detail of the abrading step at its initial step.

Fig. 7 is a further progression.

55

Fig. 8 is a final step.

Fig. 9 is a plan view illustrative of the work accomplished.

Fig. 10 a longitudinal section thereof, and Fig. 11 is a transverse section of the same.

60

In the embodiment shown I provide a base comprising supports 1 and 1¹, with longitudinal members 2 spaced therebetween. Pivoted at one end in the supports 1 is a frame 40 which carries an endless conveyor 65 3. This conveyor 3 is of a link belt type having transverse cleats 3¹ for carrying the shingles S which are fed to it so as to meet the rotary brush 30, tip or point or thin part first.

The conveyor 3 runs on a pair of sprockets 4, 5 journaled at opposite ends of the frame 40.

The sprockets 5 are driven by a chain 6 driven by a sprocket 7 on a countershaft 8 75 by a gear 9 meshing with a gear 10 on a shaft 11 which in turn is driven by a gear 12. The gear 12 is preferably driven by a pinion 13 carried on a power driven shaft. The abrading member 30 is preferably a 80 rotary wire brush of suitable stiffness to remove the free cellular body of the wood in accordance with my previous Patent No. 1,610,233, granted December 14, 1926.

The conveyor member 3 is made up of a 85 link belt comprising a pair of lateral chains 3² having roller members 14 adapted to bear on the top rail 15 of the longitudinal frame 40 of the machine. This frame as heretofore explained consists of the members 40 on 90 which the upper rails 15 are supported.

The transverse cleat members 3¹ support the shingles S in transverse rows. At suitable intervals pushing cleats 16 are provided for bearing against the butt of the shingles S so as to afford a positive feed for the shingles to the abrading brush 30. Adjacent the brush 30 is a clamping device comprising a pair of rollers 17 supported on crossed arms 18 having levers 18¹ connected by a spring 19 which acts to hold the rollers 17 down against the shingles on the way.

The longitudinal frame members 40 pivoted at 20 are raised by a cam 21 coacting

with a roller 22 on the frame 40. The cam 21 is so proportioned and timed that its lifting portion 21¹ begins to bear against the roller 22 when the shingles of any given 5 row are coming under the abrading brush 30.

- As indicated diagrammatically in Fig. 7, the brush 30 will have been brought firmly into contact with the shingle surface to give the effect shown in the section of Fig. 11.
- 10 On account of the increased thickness of the butt end of the shingles S this gives a maximum effect on the butt of the shingle where it is exposed, whereas the tip is left substantially smooth so that when laid up 15 the courses fit tightly with the unabraded lower side of the butt against the unabraded or only slightly abraded tips of the next lower course.

- In the raising movement of the frame 20 40 the row of shingles S beneath the brush 30 is brought against the yielding clamp rollers 17 so that the whole row of shingles is firmly but yieldingly held while being pushed along by the pushing cleats 16.
- 25 The shingles may be rapidly fed to the conveyor and are dropped at the opposite end in rows so that they can be conveniently rebundled for shipment.

- The brush 30 which is journaled in bearings 31 slidably mounted in the uprights 1¹ is adjustable by means of screws 32 turned by beveled pinions 33 driven by meshing pinions 34 on a shaft 35 having a squared end 36 for a crank control.
- 35 The machine is simple and inexpensive and within the reach of the ordinary dealer in shingles and is capable of giving very rapid production. Where the shingles are to be stained the conveyor may be arranged to 40 take the shingles from the delivery end of the machine and feed them to the staining machine.

- Various modifications in the structure of the conveyor and the character of the drives 45 may obviously be made without departing from the spirit of my invention if within the limits of the appended claims.

What I therefore claim and desire to secure by Letters Patent is:

- 50 1. A machine for abrasively removing a portion of the softer layers of a sawed shingle while leaving the harder intermediate layers exposed in relief, comprising a rotary abrading device, a conveyor for successively advancing a plurality of shingles past said abrading device while maintaining one surface of the shingle substantially parallel to the line of shingle travel, and means for intermittently moving said conveyor and 55 abrading device relative to each other while a shingle is disposed therebetween whereby to regulate the depth of cut.
- 60 2. A machine for abrasively removing a portion of the softer layers of a sawed shingle while leaving the harder intermediate 65

layers exposed in relief, comprising a rotary abrading device, a conveyor for successively advancing a plurality of shingles past said abrading device while maintaining one surface of the shingle substantially parallel to 70 the line of shingle travel, a spring-tensioned shingle clamp mounted adjacent to said abrading device and disposed to hold the shingles towards said conveyor as they pass said abrading device, and means for intermittently moving said conveyor and abrading device relative to each other while a shingle is disposed therebetween whereby to 75 regulate the depth of cut.

3. A machine for abrasively removing a portion of the softer layers of a sawed shingle while leaving the harder intermediate 80 layers exposed in relief, comprising a rotary abrading device, a conveyor for successively advancing a plurality of shingles beneath 85 said abrading device while maintaining one surface of the shingle substantially parallel to the line of shingle travel, and means for intermittently lifting said conveyor towards said abrading device while a shingle is disposed therebetween whereby to 90 regulate the depth of cut.

4. A machine for abrasively removing a portion of the softer layers of a sawed shingle while leaving the harder intermediate 95 layers exposed in relief, comprising a rotary abrading device, a conveyor for successively advancing a plurality of shingles beneath said abrading device while maintaining one surface of the shingle substantially parallel to 100 the line of shingle travel, a spring-tensioned shingle clamp mounted adjacent to said abrading device and disposed to maintain overhead bearing upon the shingles as they pass under said abrading device, and means for intermittently lifting said conveyor towards said abrading device while a shingle is disposed therebetween whereby to 105 regulate the depth of cut.

5. A machine for abrasively removing a portion of the softer layers of a sawed shingle while leaving the harder intermediate 110 layers exposed in relief, comprising a rotary abrading device, a pivoted frame, a conveyor carried by said frame for successively advancing a plurality of shingles beneath said abrading device while maintaining one surface of the shingle substantially parallel to the line of shingle travel, and a lifting cam for intermittently lifting said frame and 115 with it the conveyor towards said abrading device while a shingle is disposed therebetween whereby to regulate the depth of cut.

6. A machine for abrasively removing a portion of the softer layers of a sawed shingle while leaving the harder intermediate 120 layers exposed in relief, comprising a rotary abrading device, a pivoted frame, a conveyor carried by said frame for successively advancing a plurality of shingles beneath said 125

130

abrading device while maintaining one surface of the shingle substantially parallel to the line of shingle travel, a spring-tensioned shingle clamp mounted adjacent to said abrading device and disposed to maintain overhead bearing upon the shingles as they pass under said abrading device, and a lift-

ing cam for intermittently lifting said frame and with it the conveyor towards said abrading device while a shingle is disposed there-between whereby to regulate the depth of cut. 10

In testimony whereof I affix my signature.
CHARLES M. ABBOTT.
